UNITED STATES PATENT OFFICE.

RICHARD LUNDQUIST, OF LAGUNA DE TERMINOS, MEXICO.

ROTARY ENGINE.

965,640.

Specification of Letters Patent. Patented July 26, 1910.

Application filed April 9, 1910. Serial No. 554,390.

To all whom it may concern:

Be it known that I, RICHARD LUNDQUIST, a subject of the King of Sweden, and a resident of Laguna de Terminos, Mexico, have 5 invented a new and Improved Rotary Engine, of which the following is a full, clear, and exact description.

This invention relates to a new and improved engine of the rotary type, and more 10 particularly to that type of engine disclosed in my prior Patent, No. 883,034, granted March 24, 1908.

An object of this invention is to provide a device which will be simple in construction, 15 inexpensive to manufacture, strong, durable, and efficient in its operation.

A further object of this invention is to provide a rotary engine with a rotor having a plurality of pockets containing buckets 20 extending in opposite directions, whereby said rotor may be propelled in either direction.

These and further objects, together with the construction and combination of parts, 25 will be more fully described hereinafter and particularly set forth in the claims.

Reference is to be had to the accompanying drawings forming a part of this specification, in which similar characters of reference indicate corresponding parts in both 30 views, and in which—

Figure 1 is a two-plane vertical section, showing opposite phases or sections of the engine; and Fig. 2 is a view in elevation, partly in section on the line 2—2 of Fig. 1.

Referring more particularly to the separate parts of the device, 1 indicates an engine casing, which is preferably cylindrical in form and is provided with end plates 2 and 3. Rotatably journaled in bearings in 35 the end plates 2 and 3, there is provided a power shaft 4, to which is secured in any well known manner a motive member or rotor 5. This rotor is divided up into sections in any suitable manner. In each of 40 these sections, there are provided a plurality of pockets 6 and 7, the walls of which are arcuate in form, the bottom wall 8 offering a convex surface, and the end wall 9, a concave surface. These pockets 6 and 7, starting 45 from the periphery, increase in depth in a diverging manner, so as to be disposed adjacent the end walls 9. The pockets 6 face in the opposite direction from the pockets 7. In the drawings, the pockets 6 are shown 50 arranged in peripheral series in alternate

relation with series of the pockets 7. However, if desired, the series of pockets facing in one direction may be arranged side by side, and the series of pockets facing in the opposite direction may also be arranged side 60 by side. The purpose of arranging these pockets to extend in opposite directions is so that one set of pockets may be utilized to rotate the rotor 5 in one direction, and the other set of pockets to rotate the rotor 5 in 65 the opposite direction. For the purpose of more fully absorbing the steam or other motive fluid which is let into the casing 1 in a manner to be described, there are provided in each of these pockets a plurality of 70 buckets 10 and 11, preferably two in number, and secured to the rotor 5 in any well known manner. These buckets do not extend the whole width of the pockets 6 and 7, 75 but are spaced apart from the sides thereof, so as to permit the motive fluid to escape by them and exert the greater part of its force against the end walls 9. In order that the buckets 11 may be strengthened to bear the strain put thereon by the motive fluid, there 80 are provided peripherally-extending braces 12, which, further, serve the purpose of dividing up the steam in the pockets. Intermediate the adjacent pockets 6 and the adjacent pockets 7, there are provided auxiliary pockets 13 and 14, which, further, serve 85 to augment the force exerted on the rotor 5 by the motive fluid.

Arranged horizontally on diametrically opposite sides of the casing 1, there are provided steam chests 15, 16, 17 and 18, which are connected by means of pipes 19, 20, 21 and 22, (shown dotted in Fig. 1) to a common supply pipe 23. These pipes 19 to 22 meet in a common connection 24, and the flow of motive fluid therethrough is controlled by a valve 25, so that the steam or other motive fluid can be shunted to flow through the pipes 20 and 21, and thus into the steam chambers 16 and 17, thereby rotating the rotor 5 in a right-handed direction, looking at it from the front of Fig. 1; or the pipes 19 and 22 can be connected with the common supply pipe 23, thereby admitting the motive fluid to the chests 15 and 18, thus rotating the rotor in the opposite direction. The steam chests 15 to 18 are each connected to the interior of the casing 1 by jet passages 26, 27, 28 and 29, 100 of which, in the case of the steam chests 110

15 and 18, there is one for each of the series of pockets 6, and in the case of the steam chests 16 and 17, there is one for each of the series of pockets 7. It will be noted that 5 these jet passages 26 to 29 are narrow at their junction with the steam chests, or at their inlets, and gradually expand and terminate in enlarged pockets 30. This is done in order to permit the steam to expand somewhat before striking the buckets on the 10 rotor, thereby increasing the force of the steam, and the walls of these pockets, further, form abutments to absorb the reaction of the steam, and thereby augment its force on the rotor 5. Further reaction pockets 15 31 and 32 are provided in the casing 1, to augment the force exerted on the rotor by the motive fluid in either direction.

Adjacent the head and base of the casing 20 1, there are provided exhaust passages 33 and 34, of which there is one for each of the peripheral pockets 6 and 7 on diametrically opposite sides of the rotor 5.

The operation of the device will be readily 25 understood when taken in connection with the above description. The flow of motive fluid is controlled to the chests 15 to 18 by means of the valve 25. If it is desired to rotate the rotor 5 in a right-handed direction, the valve 25 is thrown so as to connect the pipes 20 and 21 with the common 30 supply pipe 23. This permits the steam to pass into the steam chests 16 and 17. The steam or other motive fluid rushes through 35 the expanding jet passages or nozzles, and being directed against the buckets in the pockets 7, rotates the rotor in a right-handed direction. Inasmuch as the buckets do not extend the full width of the pockets, the majority 40 of the force of the motive fluid is absorbed by the end walls of the pockets. As the pockets, filled with the motive fluid, approach the exhaust passages 33 and 34, the fluid naturally exhausts through these 45 passages and thereby relieves these pockets of the expended steam, and renders them in a condition ready to receive a fresh impulse from the motive fluid on the opposite side of the casing 1. This action is continuous, 50 each pocket receiving two impulses and exhausting the steam twice during a single revolution. If it is desired to reverse the engine, it is merely necessary to throw the valve 25 so as to connect the pipes 19 and 22, 55 and thus the steam chests 15 and 18, with the common supply pipe 23, when the buckets in the pockets 6 will have been brought into play.

60 While I have shown one embodiment of my invention, I do not wish to be limited to the exact structure thereof, but desire to be protected in various changes, modifications and alterations which I may make within the scope of the appended claims.

65 Having thus described my invention, I

claim as new and desire to secure by Letters Patent:—

1. A rotary engine having a rotary member provided with a plurality of separate pockets disposed about the periphery thereof and a plurality of buckets within each pocket and an engine casing inclosing said rotary member and having an outlet port and a pocket adjacent said port and from which motive fluid may expand against the 75 buckets.

2. A rotary engine having a rotor provided with a plurality of pockets in the periphery thereof, each pocket being substantially triangular in form and having two 70 inwardly-extending intersecting walls, a plurality of buckets within each pocket and a casing having an inlet port delivering substantially tangentially and a pocket communicating with said port and of substantially 80 the same form as the pocket of the rotor but reversely positioned in respect thereto.

3. In a rotary engine, the combination with a rotor having a plurality of peripherally-arranged pockets therein, each of said 90 pockets expanding gradually from the surface toward the interior, of a plurality of buckets in each of said pockets, and a casing having a motive fluid inlet and a motive fluid outlet. 95

4. In a rotary engine, the combination with a rotor having a plurality of pockets arranged in series, the pockets in some of the series extending in opposite directions 100 to the pockets in other series, each of said series having one or more buckets therein, of a casing for said rotor having a motive fluid inlet and a motive fluid outlet.

5. In a rotary engine, the combination 105 with a rotor having a plurality of pockets arranged in series, the pockets in some of the series extending in opposite directions to the pockets in other series, each of said pockets having one or more buckets therein, reinforcing braces for some of said buckets, and a casing for said rotor having a motive fluid inlet and a motive fluid outlet. 110

6. In a rotary engine, the combination with a rotor having a plurality of pockets 115 peripherally-arranged thereon, each of said pockets having a convex lower wall and a concave end wall, of one or more buckets disposed in each of said pockets and spaced apart from the side walls thereof, and a casing for said rotor having a motive fluid inlet and a motive fluid outlet. 120

7. In a rotary engine, the combination with a rotor having a plurality of pockets peripherally-arranged thereon, each of said 125 pockets having a convex lower wall and a concave end wall, of one or more buckets disposed in each of said pockets, and a casing for said rotor having a motive fluid inlet and a motive fluid outlet. 130

8. In a rotary engine, the combination with a rotor having a series of peripherally arranged pockets extending in one direction and a series of peripherally arranged pockets extending in the opposite direction, of one or more buckets in each of said pockets, and a casing for said rotor having one or more inlet passages and outlet passages for the motive fluid for said rotor, extending in juxtaposition to each of said series.

9. In a rotary engine, the combination with a rotor having a plurality of peripherally arranged pockets therein, of buckets in said pockets, and a casing for said rotor, said casing having one or more gradually expanding inlet nozzles terminating in enlarged pockets, whereby the motive fluid may expand and react on said buckets.

10. In a rotary engine, the combination with a rotor having a series of pockets peripherally arranged in said rotor of a plu-

rality of buckets disposed in each of said pockets, said rotor having auxiliary pockets of minor magnitude interposed between said first-mentioned pockets, and a casing for 25 said rotor having a motive fluid inlet and a motive fluid outlet.

11. In a rotary engine, the combination with a rotor having peripherally arranged series of pockets, each alternate series extending in an opposite direction from the juxtaposed series, of a plurality of buckets in each of said pockets, and a casing for 30 said rotor having a motive fluid inlet and a motive fluid outlet.

In testimony whereof I have signed my name to this specification in the presence of two subscribing witnesses.

RICHARD LUNDQUIST.
